(57) **CLAIM**

The ornamental design for a sport cleat, as shown and described.

DESCRIPTION

FIG. 1 is a perspective view of a sport cleat showing my new design;

FIG. 2 is a bottom plan view thereof;

FIG. 3 is a top plan view thereof;

FIG. 4 is a side elevation view thereof;

FIG. 5 is a front elevation view thereof; and,

FIG. 6 is a rear elevation view thereof.

The broken lines shown in the drawings represent portions of the sport cleat that form no part of the claimed design.

All surfaces not shown form no part of the claimed design.
